UNITED STATES PATENT OFFICE.

HARVEY M. GERSMAN, OF CHICAGO, ILLINOIS.

EXPANDED TRUSSSED BEAM.

Application filed October 9, 1924. Serial No. 742,711.

This invention relates to improvements in expanded trussed beams and more particularly to a beam which may be produced from an original rolled section, preferably 5 an I-beam section.

The principal objects of the invention are to provide an expanded trussed beam which may be economically produced, which involves economy of metal, in which the angle 10 of the struts may be selected as desired without liability of fracture and without dependence on the ductility and elasticity of the metal and which has ample strength for all practical purposes.

With the above objects in view the invention consists generally in an integral expanded beam having a single web provided with diagonal struts extending continuously between the flanges of the beam 20 and lying alternately at opposite sides of the mean plane of the web, the struts at each side being parallel to one another and extending at any desired angle to the struts at the opposite side; the invention also consists in various other novel features of construction and arrangement which will be set forth in detail as the description proceeds.

The accompanying drawings illustrate an 30 I-beam in which the features of the invention are incorporated and also stages in the production of the same.

In said drawings:

Figure 1 is an elevation of the slotted 35 blank.

Figure 2 is a section on the line 2--2 of Figure 1.

Figure 3 is an elevation of the blank after 40 the offsetting of the portions which provide the struts.

Figure 4 is a section on the line 4--4 of Figure 3.

Figure 5 is an elevation of the blank after 45 expansion.

Figure 6 is a section on the line 6--6 of Figure 5.

Figure 7 is an elevation of the completed 50 beam, and

Figure 8 is a section on the line 8--8 of Figure 7.

The blank from which the expanded beam is produced is preferably of the form shown in Figures 1 and 2, which consists of a 55 rolled I-beam shape of the usual or any desired section having a central planar web

1 and top and bottom flanges 2 and 3. The web 1 is slotted in characteristic fashion to provide for expansion in accordance with the invention. Thus the web is provided with parallel diagonal slits 4 which extend from points near one flange to points near the other and with short alining longitudinal slits 5 which, as shown, extend between corresponding ends of adjoining slits 4. Thereby the slits 4 are connected in successive pairs adjacent one of the flanges with the result that the metal between the slits not connected has the form of continuous strands 6 and the metal between the connected slits has the form of interrupted or discontinuous strands, that is to say of tongues 7 which alternate with the strands 6. As shown and preferred, the slits 4 terminate at points short of the flanges, thereby leaving beyond the slits solid web portions 1^a and 1^b but, if desired, the slits 4 may be continued right up to the flanges and these may be made of such thickness as may be deemed advisable. The strands 6 are laterally offset so as to lie in a common plane at the same side of the mean plane of the web, this being accomplished by a corrugating operation in the manner disclosed in my pending application, Serial No. 642,872; and the tongues 7 which, as shown, project from the solid portion 1^a, are in like manner bent so as to lie in a common plane at the opposite side of the mean plane of the web. These corrugating and bending operations by which the blank is given the form shown in Figures 3 and 4 may be performed in connection with the slitting or at a later stage. The strands and tongues are also preferably curved between their ends so as to have convex faces adjacent the mean plane of the web, as shown in Figure 4, and such curving may be done at the time of slitting or at a later stage.

The blank is now ready for expansion and this is accomplished by moving the flanges 100 in relatively opposite directions while maintaining their angular relation to the mean plane of the web, whereby the strands are caused to approach more nearly to perpendicular positions, as shown in Figure 5. The 105 expansion of the blank produces no change in the positions of the tongues 7; and the beam is completed by bending the tongues in the general direction of their common plane so as to cause them to extend oppositely, that 110

is to say in intersecting relation to the strands as produced by the expansion, after which the free ends of the tongues are spot welded to the adjacent solid section of the web, the completed beam being shown in Figures 7 and 8. Such bending of the tongues may be effected simultaneously with the expansion or at a later stage. If desired, and for the purpose of providing a true lattice truss, the tongues and strands may be spot welded to one another at their points of intersection, as indicated at 8 in Figure 7.

It will be obvious that the strands may be bent in the direction of their common plane to greater or less degree and that the degree to which the tongues are bent in their common plane will depend on the degree to which the strands are bent. As shown the strands have been bent to positions short of perpendicular and the tongues have been bent through and beyond perpendicular but if desired the strands may be bent through and beyond perpendicular in which case the tongues will be bent to positions suitably short of perpendicular.

Instead of locating the short slits 5 at the ends of the diagonal slits 4 they may be located as desired at points along the length 30 of the slits 4, for example at midway points. Such location of the slits 5 will result in the discontinuous strands each being in the form of a pair of originally alining tongues projecting from the respective solid portions 1^a 35 and 1^b or from the respective flanges 2 and 3 in case the solid portions are not employed. After expansion of the continuous strands as above described the originally alining tongues which, during expansion, have become relatively longitudinally offset, are bent back into alining relation and their ends connected by welding, the same welding operation being available to connect them to the continuous strands which they intersect.

Having fully described my invention, I claim:

1. An expanded trussed beam having upper and lower flanges and an integral web, said web having as parts thereof spaced diagonal integrally continuous struts and other spaced diagonal struts alternating with and extending at angles to the first named struts, the second named struts being continuous by virtue of differently located integral and applied connections.

2. An expanded trussed beam having upper and lower flanges and an integral web, said web having solid portions adjacent the flanges and spaced diagonal integrally continuous struts integrally connected to the solid portions, and other spaced diagonal struts extending between the solid portions and alternating with and extending at angles to the first named struts, the second named struts being continuous by differently

located integral and welded connections with adjacent parts of the web.

3. An expanded trussed beam having upper and lower flanges and an integral web, said web having a series of spaced diagonal integrally continuous struts and a second series of spaced diagonal struts alternating with and extending at angles to the first named struts, the second named struts being continuous by virtue of differently located integral and welded connections with adjacent parts of the web and the struts of at least one series being laterally offset relatively to the mean plane of the web.

4. An expanded trussed beam having upper and lower flanges and an integral web, said web having a series of spaced diagonal integrally continuous struts and a second series of spaced diagonal struts alternating with and extending at angles to the first named struts, the second named struts being continuous by virtue of differently located integral and welded connections with adjacent parts of the web, the struts of the two series being laterally offset at opposite sides of the mean plane of the web.

5. An expanded trussed beam having upper and lower flanges and an integral web, said web having a series of spaced diagonal integrally continuous struts and a second series of spaced diagonal struts alternating with and extending at angles to the first named struts, the second named struts being continuous by virtue of differently located integral and welded connections with adjacent parts of the web, the struts being suitably secured together at their points of intersection and the struts of at least one series being laterally offset relatively to the mean plane of the web.

6. An expanded trussed beam having upper and lower flanges and an integral web, said web having a series of spaced diagonal integrally continuous struts and a second series of spaced diagonal struts alternating with and extending at angles to the first named struts, the second named struts being continuous by virtue of differently located integral and welded connections with adjacent parts of the web, the struts of the two series being laterally offset at opposite sides of the mean plane of the web and being suitably secured together at their points of intersection.

7. An expanded trussed beam having upper and lower flanges and an integral web, said web having spaced diagonal integrally continuous and integrally connected struts and having other spaced diagonal struts alternating with and extending at angles to the first named struts, the second named struts being each integrally connected to the web at one end and having an applied connection to the web at its other end.

8. An expanded trussed beam having up-

upper and lower flanges and a web integral with said flanges, said web having as parts thereof parallel integrally continuous diagonal struts and other parallel diagonal struts 5 extending at angles to the first named struts and integrally connected to the web, said last named struts having points of interruption at which they are united to adjacent parts of the web by applied connections and 10 thereby made continuous.

9. An expanded trussed beam having upper and lower flanges and a web integral with said flanges, said web having as parts thereof parallel integrally continuous diagonal struts and other parallel diagonal struts 15 extending at angles to the first named struts and integrally connected to the web, said first and last named struts being offset laterally relatively to one another and said 20 last named struts having points of interruption at which they are united to adjacent parts of the web by applied connections and thereby made continuous.

10. An expanded trussed beam having upper and lower flanges and a web integral with said flanges, said web having as parts thereof parallel integrally continuous diag-

onal struts and other parallel diagonal struts extending in intersecting relation to the first named struts and integrally connected to the web, said last named struts being connected at their points of intersection to the first named struts and having points of interruption at which they are united to adjacent parts of the web by applied 30 connections and thereby made continuous. 35

11. An expanded trussed beam having upper and lower flanges and a web integral with said flanges, said web having as parts thereof parallel integrally continuous diagonal struts and other parallel diagonal struts 40 extending in intersecting relation to the first named struts and integrally connected to the web, said first and last named 45 struts being offset laterally relatively to one another and said last named struts being connected at their points of intersection to the first named struts and having points of interruption at which they are united to adjacent parts of the web by applied connections and thereby made continuous. 50

In testimony whereof I affix my signature.
HARVEY M. GERSMAN.
